Primary Examiner — Ian Simmonds*Assistant Examiner* — Shannon Morgan(74) *Attorney, Agent, or Firm* — Knobbe Martens Olson & Bear LLP(57) **CLAIM**

We claim the ornamental design for a hopper, as shown and described.

DESCRIPTION

FIG. 1 is a top, front, and left side perspective view of a hopper showing our new design;

FIG. 2 is a rear, bottom, and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in FIGS. 1-8 represent portions of the hopper that form no part of the claimed design.

1 Claim, 7 Drawing Sheets(56)
